US0D1003261S

(12) **United States Design Patent** (10) **Patent No.:** **US D1,003,261 S**
(45) **Date of Patent:** **** Oct. 31, 2023**

(54) **NETWORK VIDEO RECORDER**

(71) Applicant: **Zhanghuang Chen**, Zhuhai (CN)

(72) Inventor: **Shengjun Li**, Zhuhai (CN)

(**) Term: **15 Years**

(21) Appl. No.: **29/863,386**

(22) Filed: **Dec. 19, 2022**

(51) LOC (14) Cl. **14-03**

(52) U.S. Cl.

USPC **D14/125**

CLAIM

The ornamental design for a network video recorder, as shown and described.

DESCRIPTION

FIG. 1 is a front, right, and top perspective view of a network video recorder, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a sectional view thereof taken in the direction of the arrows along the line 9-9 in FIG. 3.

The broken lines depict portions of the network video recorder that form no part of the claimed design.

1 Claim, 9 Drawing Sheets
